(57) **CLAIM**

The ornamental design for a video game portal, as shown and described.

DESCRIPTION

FIG. 1 is a perspective view of a first embodiment of a video game portal embodying our new design;

FIG. 2 is a top view of the video game portal of FIG. 1;

FIG. 3 is a right side view of the video game portal of FIG. 1;

FIG. 4 is a left side view of the video game portal of FIG. 1;

FIG. 5 is a bottom view of the video game portal of FIG. 1;

FIG. 6 is a rear view of the video game portal of FIG. 1;

FIG. 7 is a front view of the video game portal of FIG. 1;

FIG. 8 is a further perspective view of the video game portal of FIG. 1;

FIG. 9 is a perspective view of a second embodiment of a video game portal embodying our new design;

FIG. 10 is a top view of the video game portal of FIG. 9;

FIG. 11 is a right side view of the video game portal of FIG. 9;

FIG. 12 is a left side view of the video game portal of FIG. 9;

FIG. 13 is a bottom view of the video game portal of FIG. 9;

FIG. 14 is a rear view of the video game portal of FIG. 9;

FIG. 15 is a front view of the video game portal of FIG. 9; and,

FIG. 16 is a further perspective view of the video game portal of FIG. 9.

The broken lines indicating environment is for illustrative purpose only and forms no part of the claimed design.

1 Claim, 8 Drawing Sheets
